UNITED STATES PATENT OFFICE.

ROBERT THOMAS MULLINS, OF BROOKLYN, NEW YORK, ASSIGNOR TO A. G. SPALDING & BROS., OF NEW YORK, N. Y., A CORPORATION OF NEW JERSEY.

HEAD GUARD.

Application filed November 1, 1926. Serial No. 145,452.

This invention relates to protective gear, and more particularly to provide an improved body protector for a participant in a collusive athletic contest, such, for instance, as a 5 player in a football game.

One of the objects of the invention is to provide an improved head-guard of the helmet type.

An important object of the invention is to 10 provide an improved type of head-guard having portions, layers of other subdivisions acting as form-holding and/or buffer functioning elements which are so relatively assembled and secured in place as adequately to protect 15 the wearer of the head-guard as well as an opponent a part of whose body is brought into collusive contact with such head-guard. In other words, an important object of the invention is to provide a new and improved 20 head-guard which shall do what previous head-guards have done, that is, completely protect the wearer, but also one which shall not be a potentially dangerous instrumentality in regard to an opponent. The attainment 25 of this object is of considerable importance, particularly in a helmet type of head-guard, inasmuch as such head-guards commonly include localized block-like or rib-like or similar protective subdivisions which project outwardly, either directly from the head 30 of the wearer or from a hood-like article of cranial apparel made up of properly cut and stitched together sheet elements.

The various other objects and advantages 35 of the invention will be specifically pointed out or apparent hereinafter, in the course of a description of a preferred one of the various possible forms of the invention as shown in the accompanying drawing, it being understood, of course, that such form is merely 40 illustrative of one combination and arrangement of parts calculated to attain the objects of the invention, pursuant to present preference.

45 In said drawing:

Fig. 1 shows a preferred form of the invention in perspective; and

Fig. 2 is a slightly enlarged fragmentary section taken on the line 2—2 of Fig. 1.

50 The exemplifying embodiment of the invention shown in the drawing as constituting a form of the invention as at present preferred, includes, as is familiar in the art, a top-cranial hood 3, having various ventilation holes 4, and equipped on its outside with a plu-

rality of rib-like protective structures 5. In the present case, the leather or other outer coverings for these ribs 5, are transversely arched, and then stitched along their longitudinal margins to an outer skin 6 for the hood 3, which skin also may be of leather. This transverse arching of the rib coverings affords a longitudinal rib pocket in which is disposed the filler material. The ribs 5 are arched upwardly along their lengths to conform to the 60 rotundity of the hood, and thus rise from circumferentially spaced points near the lower bounding edge of the hood to converge toward the apex of the hood and there intersect.

The rib pockets just referred to terminate at the line of stitching 7 around the lower margin of the cranial hood; certain of the rib coverings, however, depending below such hood, as indicated at 8, for more or less hingedly or flexibly suspending a lower-head-guard portion 9 having depending tabs or ear-lap portions 10.

Lower head-guard portion is stitched about its margin as indicated at 11, such stitching 80 also securing the lower head-guard portion to the lower ends of the rib covers, and likewise serving to mount on said lower head portion a brow-guard member 12, as indicated at 11^a. This protective structure 12 is secured to hood 85 3 by the latter's stitching 7, as indicated at 7^a.

It will be seen from the foregoing that the protective subdivision 12, as well as the ribs 5, take part, by means of their leather or similar covers, in providing a more or less flexible 90 connection between the hood portions, and a connection more freely flexible at the back of the new head-guard than at the front.

As will be seen clearly from Fig. 1, the sheet of leather or the like forming the cover for 95 the protective subdivision 12 is arched transversely to provide a pocket for filler material.

In a similar manner, sheets of leather or the like are cut and transversely arched to provide pockets for filler material, and to be marginally stitched to the outer skin of the lower hood portion to provide a horizontally extending protective structure 14 at the back of the neck and to provide a pair of annular ear protecting structures 15 for each of the 105 tabs 10.

As in the case of the hood 3, the lower hood portion 10 has an outer skin 16 of leather or similar material.

It will be understood that the filler mate-

rial for the various localized protective structures 5, 12, 14 and 15 is of a shock absorbing character, as is the inner lining for the hood 3 and the lower hood portion 10. Such lining, 5 as is familiar in the art, is a lining of shock absorbing material such as a lining 17 of felt.

I have discovered that the various objects of the invention may be attained, as well 10 also as the additional one of providing a comparatively inexpensive head-guard and one which may be worn with maximum comfort, when the various shock absorbing materials employed, (a) for filling the localized 15 protective structures 5, 12, 14 and 15 and (b) for lining the head embracing head portions, are of different degrees of elastic resistance to deformation by compression, particularly when the material having the greatest 20 degree of such elasticity is used as the filler for the protective structures 5, 12, 14 and 15. I have also found that then all the 25 objects of the invention are attained even when the thickness of the lining for the hood portions is much thinner than heretofore, so as to be rather a sheet than a pad. A very 30 satisfactory and practical combination for thus carrying out the invention is had when a material, as indicated at 18 in Fig. 2, having the qualities of foam rubber, acts as the filler material for the protective structures 5, 12, 14 and 15, and when the material for the thin lining 17 has the qualities of felt.

I claim:

35 1. In a head guard, a top cranial hood provided on its outside with a plurality of rib like protective structures of flexible material extending radially from the center of said

hood, certain of said rib like structures extending downwardly below the hood, and a lower head guard portion stitched to the 40 lower ends of the downwardly extending rib like structures whereby the lower portion is flexibly connected to the hood portion by said ribs, said lower head guard portion being arranged to cover the back of the 45 wearer's neck and having a rib like protective structure extending horizontally thereacross, annular ear protecting ribs located forwardly of the last mentioned rib-like protective structure and at the ends thereof. 50

2. In a head guard, a top cranial hood provided on its outside with a plurality of rib like protective structures of flexible material extending radially from the center of said hood, certain of said rib like structures extending downwardly below the hood, and a lower head guard portion stitched to the 55 lower ends of the downwardly extending rib like structures whereby the lower portion is flexibly connected to the hood portion by said ribs, said lower head guard portion being arranged to cover the back of the wearer's neck and having a rib like protective structure extending horizontally thereacross, 60 annular ear protecting ribs located forwardly of the last mentioned rib-like protective structure and at the ends thereof, each of said rib like structures consisting of an arched strip of leather marginally stitched to the parts over which it extends and having 65 a filling of resilient material. 70

In testimony whereof I affix my signature.

ROBERT THOMAS MULLINS.
